WILLIAM DUNSON, OF INDIANAPOLIS, INDIAN

REINFORCED CONCRETE TIE.

No. 909,378.

Specification of Letters Patent

Patented Jan. 12, 1909.

Application filed March 27, 1908. Serial No. 423,632.

to all whom it may concern:

Be it known that I, WILLIAM DUNSON, citizen of the United States, residing at Indianapolis, in the county of Marion and State of Indiana, have invented certain new and useful Improvements in Reinforced Concrete Ties, of which the following is a specification, reference being had therein to the accompanying drawing.

10 This invention relates to an improvement in reinforced concrete railway ties herein-after described in the specification and particularly pointed out in the claims.

The object of this invention is to provide a reinforcing means for strengthening the concrete body portion of the tie to prevent disintegration thereof due to the jarring caused by the passage of trains along the track and resting on said tie, to construct such a tie 15 that the reinforcing means thereof will be completely surrounded on all sides and enveloped by the concrete to protect the metal, of which the reinforcing means is constructed, from the action of the atmosphere; also, 20 to construct such reinforcing means with integral block receiving chairs in the recesses of which cushion blocks of a resilient material, are fitted upon which said rails rest and to which they are spiked or otherwise secured. 25

30 I attain these objects by means of the reinforced concrete tie illustrated in the accompanying drawings in which like numerals of reference designate like parts throughout the several views.

35 Figure 1 is a top view of my tie; Fig. 2 is a longitudinal sectional view of the same, taken along the line 2—2 in Fig. 1; Fig. 3 is a transverse sectional view of the tie taken along the line 3—3 in Figs. 1 and 2; Fig. 4 is 40 a transverse sectional view of the tie taken along the line 4—4 in Figs. 1 and 2; and, Fig. 5 is a view of the mold showing the reinforcing core situated therein and the concrete molded around it.

45 The metallic core portion of the tie, is provided with block holding chairs each of which is composed of the base portion 1 and the inclined side portions 2 and 3 forming a block receiving channel into which a dovetail

50 formed block 4 of an elastic material, such as wood, is fitted to form a cushion whereon the rails 5 rest and are secured by spikes 6 in the usual manner. The sides 2 and 3 are reinforced by the braces 7 and 8 which extend 55 from the reinforcing tie bar to the top side portions of the sides 2 and 3, and said braces

are provided for the purpose of maintaining said sides rigidly in position and preventing them being sprung outwardly, so that said blocks 4 will at all times fit snugly between them. The block receiving channels formed by the sides 2 and 3, are tapered in a longitudinal direction, so that the wider end of the channel of the chair, situated at one end of the tie, will be situated at the front edge 65 of the tie, while the wider side of the channel of the chair will be situated at the rear edge of the tie or in other words the longitudinal tapers of said channels in each tie will alternate necessitating the dovetailed cushion 70 block to be driven into the channels situated at one end of the tie from the front edge of the tie and the other dovetailed cushion block to be driven into the channel, situated at the other end of the tie, from the rear edge 75 thereof, so that while a train is moving in one direction over the rails it will tend to move the rail situated at the one end of the tie longitudinally to loosen the cushion block on which it bears, the opposite companion rail 80 will tend to tighten the cushion block on which it bears.

The chairs are connected and tied to maintain their proper distance apart by a connecting means composed of the upper arch 85 bar member 9 and the lower arch bar member 10, and said chairs are connected thus in order to secure the proper amount of elasticity and strength to the tie so as to avoid an excessive degree of bending movement being 90 applied to the concrete portion of the tie to prevent a crumbling or disintegration thereof.

The construction of this tie is accomplished with facility and cheapness as follows:—The metallic reinforcing core of the 95 tie is placed in position edgewise in a suitable rectangular molding flask, as the rectangular molding flask, shown in Fig. 5, and the concrete which is made very liquid, is poured around the reinforcing core composed of the 100 chairs and the arch bars, previously described and into the spaces situated between the different members of said reinforcing core, to completely surround and inclose said core to form a solid compact body.

I claim:

1. In a reinforced concrete tie, the combination with end chair members having block receiving channels, said channels being narrower at their top portions than their bottom portions and tapered toward one of their ends, of upper and lower bar members con-

105

110

necting said chairs, and a concrete body surrounding and inclosing said chairs and said upper and lower bar connecting members.

2. In a reinforced concrete tie, the combination with end chair members having block receiving channels, said channels being narrower at their top portions than their bottom portions and the channel situated at one end of said tie, tapered longitudinally and opposite to the longitudinal taper of the other companion channel, of upper and lower arch

bar members having their concave sides facing each other and connecting said chairs, and a concrete body surrounding and inclosing said chair members and said arch bars. 15

In testimony whereof I affix my signature in presence of two witnesses.

WILLIAM DUNSON.
